UNITED STATES PATENT OFFICE.

GEORGE O'NEILL, OF MONCTON, NEW BRUNSWICK, CANADA.

FUEL-SAVING DEVICE.

1,153,333.

Specification of Letters Patent. Patented Sept. 14, 1915.

Application filed April 12, 1915. Serial No. 20,720.

To all whom it may concern:

Be it known that I, GEORGE O'NEILL, a subject of the King of Great Britain, and resident of Moncton, in the Province of New Brunswick, Dominion of Canada, have invented certain new and useful Improvements in Fuel-Saving Devices, of which the following is the specification.

This invention relates to improvements in fuel saving devices particularly adapted for household stoves and the like.

At the present time the products of combustion are usually discharged to the stove pipe at a comparatively low temperature, thereby causing a considerable loss of fuel, and the principal object of this invention is to effectively mix a stream of superheated air with the primary products of combustion so effecting a second combustion, resulting in the elimination of smoke and consequently greater efficiency.

Further objects are to permit of the device being readily fitted to stoves at present in use, to simplify the construction and generally adapt the several parts to better perform the functions required of them.

With the above objects in view, the invention consists essentially of the improved construction particularly described and set forth in the following specification and accompanying drawings forming part of the same.

In the drawings, Figure 1 is a fragmentary perspective view of a stove embodying the present invention. Fig. 2 is an enlarged sectional elevation of the air superheater. Fig. 3 is a perspective view of the outer member of the air superheater. Fig. 4 is a perspective view of the cover or inner member of the air superheater.

Like characters of reference refer to like parts in the several drawings.

Referring to the drawings, A represents a stove and B the improved air superheater mounted thereon. The said stove being of any usual type and not forming part of the present invention, it is deemed unnecessary to further describe the same.

The air superheater B is designed to replace the ordinary cover on the stove above the fire and consists of an outer cylindrical member 10 carrying on the top an outwardly extending radial flange 11 integral therewith having a recess 12 around its inner periphery. The cylinder is formed with an integral bottom having a plurality of orifices

13 therethrough adjacent to the periphery and further carries an integral upward and concentrically located baffle flange 14 which extends partially through the said cylinder.

The cylinder 10 is designed to be closed on the upper end by the cover 16 which is provided with a concentric circular depression 17 having an orifice 18 through the center thereof and a plurality of radially extending orifices 19, one of which is preferably T-shaped, the said cover being further provided with a downwardly extending baffle flange 20 adapted to be concentrically located to the flange 14 and extending below the upper edge thereof.

To control the flow of air through the orifices 19 an air valve 21 carrying a downwardly disposed central integral projection 22 is rotatably mounted in the orifice 18 and provided with a plurality of orifices 23 adapted to register with the orifices 19 when the valve is opened, the movement of the said valve being limited by the integral projection 24 engaging with the T-shaped orifice.

When the stove is in operation the smoke on its passage to the stove pipe causes an induced current of air to pass through the orifices 23 and 19 into the chamber formed by the flange 20, the cover 16 and the bottom of the cylinder 10 where it is superheated, the said air then passing through the passageway between the baffle flanges 20 and 14 and the inner periphery of the cylinder 10, being finally discharged through the orifices 13 to intermix with the smoke, causing a better and final combustion of the same.

It has been found in practice that by intermixing a stream of such superheated air with the primary products of combustion that a second combustion, causing a greater heat and reducing the clinkers to a fine ash, is brought about, thereby effecting a considerable saving in fuel.

As many changes could be made in the above construction and many apparently widely different embodiments of my invention, within the scope of the claims, constructed without departing from the spirit or scope thereof, it is intended that all matter contained in the accompanying specification and drawing shall be interpreted as illustrative and not in a limiting sense.

What I claim as my invention is:

1. In combination with a stove, a super-

- heater comprising two concentric removable griddle sections each having a depending cylindrical wall integral therewith, a cup shaped member extending upwardly between said cylindrical walls, spokes integrally connecting said cup shaped member to said outer cylindrical wall, and air admission controlling means on said inner griddle section.
- 10 2. The combination with a stove of a superheater comprising a cylindrical member having a radial flange on the upper end thereof provided with a recess in its inner periphery and orifices through the bottom, an upwardly extending baffle flange integral with the bottom and concentrically located in the cylinder, a cover adapted to engage with the recess having a depression in the center thereof provided with a cen-

tral orifice and a plurality of radially extending orifices, one of which is T-shaped, a downwardly extending baffle flange integral with the cover and concentrically located to the first said baffle flange, an air valve having a plurality of orifices therethrough, a projection integral with the air valve adapted to rotatably engage the orifice in the center of the cover, and a second projection integral with the air valve and located near the periphery thereof designed to engage with the T-shaped orifice, substantially as described. 20
25

In witness whereof I have hereunto set my hand in the presence of two witnesses.

GEORGE O'NEILL.
